CHARLES F. SMITH, OF NEW BRITAIN, AND SVEND J. HELWEG, OF HARTFORD, CONNECTICUT, ASSIGNEES TO LANDERS, FRARY & CLARK, OF NEW BRITAIN, CONNECTICUT, A CORPORATION OF CONNECTICUT

WASHING MACHINE

Application filed September 14, 1926. Serial No. 135,319.

This invention relates to washing machines of the type having a tub mounted for oscillation about a vertical axis.

The object of the invention is to provide an improved tub wherein washing of the clothes or other articles to be cleansed is effectively carried out without liability of damage to the clothes. Our improved arrangement is such that the water is constantly circulated and agitated in a manner which insures thorough and complete washing of the clothes in a relatively short time, but the action is gentle to the extent that very fragile textiles, such as frail laces, may be washed without danger of injuring the same.

Other objects will be in part obvious and in part pointed out more in detail herein-after.

The invention accordingly consists in the features of construction, combination of elements and arrangement of parts which will be exemplified in the construction hereinafter set forth and the scope of the application of which will be indicated in the appended claims.

In the accompanying drawings, wherein is shown, for illustrative purposes, one of the embodiments which the present invention may take:

30 Figure 1 is a perspective view looking down into the tub;

Fig. 2 is a view showing the tub and the fin thereof in vertical central section along the line 2—2 of Fig. 3, the base of the machine and the means for oscillating the tub being shown in elevation and more or less conventionally; and

40 Fig. 3 is a top plan view with a portion of the rim or in-turned flange of the tub removed.

Referring to the drawings in detail, A designates a base which is here shown more or less conventionally or diagrammatically, as the particular construction thereof forms no part of the present invention. B designates a spider carrying the tub and having a post b' journaled in a bearing a' on the base. C designates a crank which may be rotated by any suitable means (not shown), and this 45 crank is connected to the spider by a pitman

or connecting link D in such manner that, when the crank is rotated, the spider B, together with the tub carried thereby, will be oscillated back and forth through the desired angle, say 70°.

55 The tub E is circular in cross section and has a concave or rounded bottom 10, and the bottom gradually curves or merges without break into the cylindrical side walls of the tub. If desired, the tub may be provided at its upper edge with a rounded inturned flange 11.

60 In accordance with the present invention, the tub is provided with a single fin or baffle which, when the tub is oscillated, results in the desired circulation and agitation of the water together with the clothes immersed therein. In the present illustrative disclosure of the invention, this fin is in the form of a sheet metal plate soldered or brazed in place but, obviously, the fin could be provided by making the wall of the tub of the desired shape. This fin has a rib 12 to each side of which is a trough 13, the troughs preferably being symmetrical with respect to one 65 another and parallel to the rib. The rib, which is convex or parti-circular and preferably uniform in cross section, is inclined upwardly from the bottom of the tub to a point adjacent the upper end of the side wall thereof, as clearly shown in Fig. 2. The lower end or bottom of the rib preferably extends into the tub a substantial distance but does not extend to the center thereof. In the present illustrative disclosure, the bottom of the rib is shown as extending into the tub a distance 70 slightly greater than half the radius of the tub. The fin gradually increases in width as it progresses towards the bottom of the tub providing, so to speak, wings 14 which 75 constitute continuations of the concave side walls 15 of the rib and which wings fit in the rounded corner between the concave bottom and the cylindrical sides of the tub. The ends of these wings are substantially tangential to the tub.

80 With the arrangement described, when the tub is moving in either direction, the water, in front of that side wall of the rib which is advancing, is caused to flow generally 85 90 95 100

upwardly and circumferentially of the advancing trough and pour over the rib inwardly of the tub. The water is thrown, so as to speak, over the rib upwardly and inwardly. A more or less definite current or flow is given to the water, this current being generally across the top of the body of water away from the fin, then downwardly along that portion of the tub opposite the fin, then along the bottom of the tub toward the fin and then upwardly of the fin as previously described. Assuming for the purpose of exemplification that the fin is at the rear of the tub, then the current or flow may be described in connection with the arrows of Fig. 2 as follows: Across the top of the body of water toward the front of the tub, as indicated by the arrow 50; downwardly at the front of the tub, as indicated by the arrow 51; then rearwardly at the bottom of the tub, as indicated by the arrow 52; and then upwardly of the fin and over the rib thereof. It is understood, of course, that the flow or current just described is a more or less general one, there being a tendency for the water at the lateral sides of the tub to follow the curvature of those sides, and for some of the water at the front of the tub to be thrown back and forth. The water, together with the articles immersed therein, has a more or less rapid motion up and over the fin and a slower motion at the front. The clothes, as they pass over the fin, are changed in position, shape and relation, and as they pass toward the front of the tub and downwardly along the front they are spread out or distributed. In any event, all portions of the body of water, together with the clothes immersed therein, are caused to continuously circulate in such manner that the clothes are well distributed and spread out so that the clothes are kept from becoming bunched up or entangled and there is a complete freedom of washing action. In no instance is there a dead spot or eddy in which the clothes might collect and become entangled. The results are that the clothes are thoroughly and rapidly washed and, at the same time, the treatment is sufficiently gentle to prevent damage to the very finest kind of clothes.

By preference, the arrangement is such that the current of the water passing in one direction up and over the fin, when the tub is moving in one direction, is slightly stronger than that passing up and over the fin, when the tub is moving in the opposite direction so that there is a differential flow, so to speak, resulting in the articles being washed flowing over the fin in one direction a slightly greater number of times than in the other direction, thereby further preventing bunching or tangling of the clothes. Any suitable means for oscillating the tub in

a manner to accomplish this result may be employed, but by way of example, we have shown this means as comprising the rotating crank *c* and the connecting rod *d* eccentrically connected to the tub. The action may be described more in detail as follows, reference being particularly directed to Figs. 3 and 4: It may be assumed that the crank *c* rotates at a uniform speed in a counterclockwise direction and the radius of the large circle in Fig. 4 corresponds to the distance between the center of oscillation of the tub and the point of connection between the spider and the connecting rod *d*. It will be observed that when the crank is moving 180° through the arc *r*, *s*, *t*, that end of the pitman connected to the tub will move first clockwise, or to the right, from *r'* to *s'*, and then to the left from *s'* to *t'*. When the crank moves through 180° arc indicated by *t*, *u* and *r*, the end of the pitman connected to the tub will move to the left from *t'* to *u'* and then to the right from *u'* to *r'*, and the tub is moved a greater angular distance and therefore more rapidly when the crank is moving through the 180° arc *t*, *u*, *r*, than when the crank is moving through the 180° arc *r*, *s*, *t*. This means that the reversal of movement of the tub, when the crank passes the point *u*, is quicker than when the crank passes through the point *s*. The initial movement of the tub on a stroke in a clockwise direction, that is to the right, is greater than the initial movement of the tub in the opposite direction. Also, the tub approaches the end of its stroke in a counterclockwise direction more rapidly than it does the end of its stroke in the other direction. In other words, the tub approaches and leaves one limit of its movement slightly more rapidly than the other limit. As a result of this action, the flow of water over the fin is slightly greater in one direction than in the other, in the present illustrative example, the flow over the fin upon initial clockwise movement of the tub being slightly greater than upon initial counterclockwise movement. Obviously, other driving means than that illustrated may be employed to obtain this result, it being understood that the foregoing explanation is by way of example only, and that it is immaterial as to which direction the tub is moving when the greater flow of water over the fin is obtained. In Fig. 4, the angular distance which the tub moves for each successive 90° movement of the crank is indicated merely to make the illustration clearer.

We have found that a tub having the relative proportions shown in the drawings effects excellent results, but obviously the invention is not limited to the exact proportions shown and many changes could be made in the above construction without departing

from the scope of the appended claims, it being intended that all matters contained in the above description or shown in the accompanying drawings shall be interpreted as illustrative and not in a limiting sense.

5 We claim as our invention:

1. In a washing machine, a vertical tub mounted for rotary oscillation and provided with a single inclined fin, said fin having a 10 central convex rib with symmetrical concave side walls merging into the side wall of the tub.

15 2. In a washing machine, a vertical cylindrical tub mounted for rotary oscillation and provided with a single inclined fin and with a bottom which is concavely rounded throughout its entire area, said fin having a central rib with symmetrical concave side walls merging into the side walls of the tub, 20 the bottom of said rib projecting into the tub and being spaced at substantial distances from the side wall and the center of the tub.

25 3. In a washing machine, a vertical tub mounted for rotary oscillation and provided with a single fin including an inclined convex rib and a trough to each side of the rib.

30 4. In a washing machine, a vertical tub mounted for rotary oscillation and provided with a cylindrical side wall and a concave bottom rounding into said side wall, said tub having a single fin inclined from the bottom of the tub to the side wall thereof, said fin including a central convex rib with a trough 35 at each side thereof, and said fin having at each side a wing fitting in the rounded corner between the bottom of the side wall of the tub.

40 5. In a washing machine, a vertical cylindrical tub mounted for rotary oscillation and provided with a bottom which is concavely rounded throughout its entire area, and a single fin extending from said concave bottom to the side wall of the tub and extending 45 above the normal level of the water within the tub.

50 6. In a washing machine, a vertical cylindrical tub mounted for rotary oscillation and provided with a bottom concavely rounded throughout its entire area and a single inclined fin extending above the normal level of the water within the tub, said fin having a central rib with symmetrical concave side walls merging into the side walls of the tub, 55 the bottom of said rib projecting into the tub and being spaced at substantial distances from the side wall and the center of the tub.

60 7. In a washing machine, a rotary oscillating vertical tub provided with a single fin inclined upwardly from the bottom of the tub to one side thereof, said fin being symmetrical in cross section and of progressively increasing width as it approaches the side of the tub.

8. In a washing machine, a vertical cylindrical tub mounted for rotary oscillation and provided with a bottom concavely rounded throughout its entire area, and a single inclined fin extending from said concave bottom to the side wall of the tub, the side walls of said fin being concave and merging into the wall of the tub.

70 9. In a washing machine, a tub mounted for oscillation about a vertical axis and provided with a single rib on one side thereof, and means for oscillating said tub arranged to cause a greater current of water to flow over the tub when the tub is moving in one direction than when it is moving in the other.

75 10. In a washing machine, a vertical cylindrical tub mounted for oscillation about a vertical axis and provided with a single fin at one side arranged to cause the water, in advance of the fin, to flow generally upwardly and pour inwardly of the tub over the fin, and means for oscillating said tub arranged to cause a greater flow of water over the fin in one direction than in the other direction.

80 11. In a washing machine, a rotary oscillating vertical tub provided with a single fin inclined upwardly from the bottom of the tub to one side thereof, and means for oscillating said tub arranged to cause a quicker reversal at one limit of movement than at the other limit.

85 12. In a washing machine, a vertical cylindrical tub mounted for rotary oscillation and provided with a single fin at one side arranged to cause the water to flow along the top away from the fin, then down that side of the tub opposite the fin, then along the bottom of the tub towards the fin, and means for oscillating the tub so arranged that the initial movement of the tub in one direction is faster than the initial movement of the tub in the opposite direction.

90 13. In a washing machine, a tub mounted for oscillation about a vertical axis and provided with a single rib on one side thereof arising above the normal level of the water in the tub, and means for oscillating said tub so arranged that one stroke of the tub is faster at its beginning and slower at its end than the other stroke.

95 14. In a washing machine, a rotary oscillating vertical tub provided with a single fin inclined upwardly from the bottom of the tub to one side thereof, said fin having concave side walls merging into the side walls of said tub, and means for oscillating said tub arranged to give a faster movement to the tub as it approaches and leaves one reversal point than at the other reversal point.

100 15. In a washing machine, a rotary oscillating vertical tub provided with a single fin inclined upwardly from the bottom of the tub to one side thereof, said fin gradually increasing in width as it progresses towards the wall.
